UNITED STATES PATENT OFFICE.

GEORGE F. SMITH, OF NEW YORK, N. Y., ASSIGNOR OF ONE-HALF TO HARRY H. EPSTEIN, OF NEW YORK, N. Y.

ENVELOP-LOCK.

1,177,364.

Specification of Letters Patent. Patented Mar. 28, 1916.

Application filed November 20, 1915. Serial No. 62,521.

To all whom it may concern:

Be it known that I, GEORGE F. SMITH, a citizen of the United States, and a resident of the city of New York, borough of 5 Manhattan, in the county and State of New York, have invented a new and Improved Envelop-Lock, of which the following is a full, clear, and exact description.

This invention relates to sheet metal fasteners adapted especially for sealing or locking envelopes or similar containers so that they cannot be opened without detection.

Among the objects of the invention, therefore, is to provide an improved form 15 of fastener adapted for the above stated purpose.

Another object of the invention is to construct a paper or similar container adapted for use especially with my improved sheet 20 metal device.

With the foregoing and other objects in view the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like 25 reference characters designate the same parts in the several views, and in which—

Figure 1 is a perspective view of the sheet metal fastener or locking device in the form assumed by it just prior to application to the container; Fig. 2 is a perspective view of a paper container shown in the form of an envelop, the outer sealing flap being open in normal position and showing the lower flap turned down from its normal 40 position to better indicate the relative arrangement of the end flaps; Fig. 3 is a central transverse sectional view indicating the envelop locked; and Fig. 4 is a longitudinal sectional view on the line 4—4 of

Fig. 3.

Referring now more particularly to the drawings I show at 10 a sheet metal device formed preferably by stamping from a strip of metal of uniform thickness and comprising upper and lower tongues or plates 11 and 12 respectively connected along a bending line 13. The tongues are preferably of the same form and size and are adapted to overlap each other when the device is in 55 locking position.

The upper tongue is formed with a pair of prongs 14 struck out from the body of the plate and downwardly toward the bottom plate, the points of the prongs being spread apart slightly to a distance greater than the distance between the bases of the prongs. The bottom plate 12 is provided with a pair of slits 15 formed parallel to each other longitudinally of the plate, and that portion 16 of the plate between the slits is bent downwardly from the main portion of the plate so as to provide lateral openings between the ends of the portion 16 and the main body of the plate. The portion 16 or anvil is arranged in such position as to be engaged by the points of the prongs when the two plates are bent against or toward each other, the slits being slightly farther apart than the distance between the points of the prongs. 75

The container is shown in the form of an envelop made along somewhat conventional lines in so far as the front 17, end flaps 18 and bottom flap 19 are concerned. The flaps 18 are formed to overlap each other 80 at the middle portion of the container, and the bottom flap is designed to be gummed directly upon the overlapping portions of the end flaps in the usual manner. This overlapping of the end and bottom flaps 85 may constitute what is termed an anchor portion of the container.

The upper sealing flap 20 is provided with a tongue 21 at its central portion and at its free edge. This tongue is of sufficient length 90 to lie double squarely upon the overlapping portions of the sealing flaps 18 and 19. The tongue may be secured in any suitable manner to the flap 20 but preferably is made integral therewith as indicated. The extreme 95 end of the tongue 21 is bent beneath the main portion of the tongue and adapted to lie in a plane between the planes of the upper flap 20 and the lower flap 19.

The manner of application and operation 100 of the invention may be briefly described as follows:

The plate 11 is slipped into the space between the two parts of the tongue with the free edge of the plate within the crotch 105 formed by the two parts of the tongue and with the points of the prongs projected through the free end of the tongue inwardly with respect to the envelop when closed.

After thus connecting the fastener to the 110

tongue 21 the base plate 12 is slipped beneath the overlapping central portions of the end and bottom flaps, the upper flap being bent to accommodate this action. All 5 the parts will now be in position approximating the final position, and a firm pressure or blow upon the outer surface of the tongue made applicable at the same time upon the upper plate 11 of the fastener will 10 force the points of the prongs 14 directly through the overlapping portions of the flaps 18 and 19 and against the upper surface of the anvil 16. Since the prongs are deflected slightly away from each other, the 15 application of force thereto will cause the points thereof to be directed outwardly laterally from each other through the slits, and thereby the prongs will be securely clenched through the free end of the tongue, the overlapping portions of the flaps 18 and 19, and 20 beneath the side portions of the base 12, as shown in Fig. 4, though in a somewhat distorted position due to the fact that the paper in practice will not be so thick as indicated 25 by the figure. The anvil constitutes the clencher and at the same time protects the contents of the container (not shown) from damage by the points of the prongs. The device is cheap in construction, simple or 30 application, and of such a nature as to dispense with the necessity for applying gum or moisture to the sealing flap 20, and at the same time providing a means whereby the container is practically locked against 35 surreptitious opening. It is obvious, however, that the sealing flap 20 may be provided with gum, if desired, for additional security, though my purpose is to dispense with moisture or gum on this part. It will be appre-

ciated that the outer or middle portion of 40 the tongue constitutes a cover for the fastening plate.

I claim:—

1. The combination with a container having a fixed anchor portion and a closing 45 flap having a tongue folded upon itself over said anchor portion, of a sheet metal fastening device comprising two plates connected along one edge so as to bend toward each other, one of the plates having a pair of 50 prongs directed toward the other plate and said other plate having an anvil portion and a pair of slits at the ends thereof through which said prongs are adapted to be forced and clenched by contact with the anvil portion, one of said plates being slipped beneath the anchor portion of the container and the other being inserted into the folded tongue aforesaid, substantially as set forth.

2. The herein described fastener comprising a unitary sheet metal structure bent upon itself to form a pair of plates, one plate having a pair of prongs struck downwardly therefrom toward the other plate and the other plate having a pair of parallel slits through which the points of said prongs are adapted to be forced, that portion of the latter mentioned plate between the slits being bent away from the first mentioned plate to form an anvil against which 65 the points of the prongs are caused to impinge and be bent outwardly through the 70 slits.

GEORGE F. SMITH.
